PRICEOMETER

Edward Stanley Griffith, Oneida County, N. Y.

Application April 11, 1930. Serial No. 443,574

2 Claims. (Cl. 235—86.)

This invention appertains to improvements in priceometers and the like generally, and has for its main object to provide a type of the same for giving direct readings of the prices of a number 5 of commodities, such as different feeds and grains bought or sold by the hundred weight or ton and throughout a wide range of fluctuation in the prices of the commodities.

At the present time, grains and feeds are distributed from thousands of mills throughout the country to other thousands of stores or stations which, in turn, redistribute the commodities to far reaching stores and stations for supplying the users in local communities. The enormity 15 of this great system of distribution brought about the creation of centralized distributing points or zones, which, in turn, are divided into other or minor distributing points or zones radiating therefrom. In the organization of these major 20 and minor points of distribution, certain percentages or rates of increase in buying and selling prices of the different commodities are allowed in the different minor zones over the basic selling prices established from time to time in the 25 major or central zones and much labor is involved in computing the prices of each of a number of different commodities by hand, in view of the sometimes rapid fluctuation in prices in the basic or central zones and since such computations must consider questions of basic price, 30 rate of increase in each minor zone and various commissions allowed in the different minor zones.

It is therefore another object of the invention to provide an apparatus of the class set forth 35 which will avoid the necessity for the computing of the buying or selling prices of commodities separately for each business transaction or for each fluctuation in such prices or the calculations of the prices to include rate increases and commissions usual in feed and grain buying and selling in the different localities or zones.

A further object of the invention is to provide an apparatus of the character mentioned, which will be extremely simple in construction and design, comparatively inexpensive to manufacture and install and highly efficient but easy in operation, and which will give to industry an accurate ready reckoning means in saving time and expense as well as in avoiding costly errors arising from computations hurriedly made by human agencies.

With the foregoing and other equally important objects and advantages in view, the invention resides in the certain new and useful combination, construction and arrangement of parts,

as will be hereinafter more fully described, set forth in the appended claims and illustrated in the accompanying drawings, in which:

Figure 1 is a front elevation of a practical embodiment of the invention; 60

Figure 2 is a vertical section, taken on the line 2—2 of Figure 1;

Figure 3 is a view similar to that of Figure 2, but taken on the line 3—3 of Figure 1;

Figure 4 is a slightly enlarged front elevation 65 of a part of the apparatus;

Figure 5 is an enlarged fragmentary perspective view of a portion of the latter part of the apparatus and showing the manner of mounting certain of the card holders therein; also the 70 manner of positioning a name card and its companion rate card in one of the latter;

Figure 6 is an enlarged fragmentary portion in plan of the computed price tape;

Figure 7 is a plan view of one of the commodity 75 indicating or name cards and Figure 7a is a fragmentary plan view of a companion rate card, showing the selling prices tabulated thereon for fractional units of weight of the particular commodity. 80

Referring to the drawings, wherein like characters of reference designate corresponding parts in the several views thereof, the embodiment of the invention, as shown therein by way of example only, is constituted generally in a cabinet 85 formed of two separate sections 10 and 11, which, when installed for use, will preferably be secured together, in side to side relation, by means of a pair of coupling members 12. These coupling members 12 are each preferably in the 90 form of an elongated bar extending between the sections 10 and 11 at one side of the same and secured as for instance, at one end by means of thumb bolts or the like 13 to the section 11 and at its other end by having a slot 14 95 therein engaged over a stud 15 carried by the section 10. This stud 15 has an elongated head 15' which is swivelled on the free end of the stud so as to be turned to a secured position crosswise of the member or bar 12 after the slot has been engaged over the stud below the same. 100

Journaled horizontally within the cabinet section 10 is a series of rollers 16, 17, 18 and 19 105 over which an endless tape 20 is trained. The traction roller 16 for imparting travelling movement to the tape 20, being arranged with one end of its supporting shaft projected outwardly of the adjacent side of the cabinet casing to re- 110

ceive a finger piece 16' thereon for its required manipulation.

Mounted within the open front of the cabinet section 10 is a face plate 21, which is provided with a series of spaced horizontal openings or slots 21' to expose indicia arranged on the opposed side of the tape 20 through the same. This face plate 21 is enclosed by a cover, consisting of a frame 22 having its open center closed 10 by a pane of glass or other transparency 22' so that the major portion of the face plate 21 will be exposed therethrough. The face plate 21 is to be suitably marked in the space thereon above the uppermost of the slots 21', with the trade name of the device and between the latter and the said slot with the terms of unit weights, such as "Ton" and "Hundred weight (cwt.)", of commodities whose selling price, together with added rates and commissions are tabulated on the tape 20 and are to be ascertained at the 15 sight openings 21', the term "Ton" being preferably arranged toward the left hand end of the said slot and "Cwt." toward the right hand end thereof.

25 In the cabinet section 11, to be employed in connection with the cabinet section 12 is positioned two horizontally spaced strips or bars 23, on the front edge of each of which a plurality of card holders 24 are dependingly supported, the same being preferably hinged, as at 30 25, in place from their upper ends. The bars or strips 23 are of a less width than the depth of the cabinet section in order that the card holders 24 will be suspended immediately inward of the pane of glass or other transparency 26' closing the open center of the closure frame 26, which is, in turn, hinged, as at 27, to the upper edge of the cabinet section. A reserve supply 35 of the cards to be interchangeably employed in the card holders 24 may be stacked on the bottom wall of the cabinet section 11 and on the upper side of the lower of the bars or strips 23 in rear of transversely extending retaining members or strips 28.

40 Each of the card holders 24 is made of a vertically elongated piece of sheet metal which has its opposite side edges angularly bent to provide outwardly and inturned flange portions 24' to provide opposed channel-ways within the same for the reception of the opposite side edges of the card, the lower ends of the channel-ways being closed by an annular flange 24" formed at the lower end of the holder.

45 In the use of the device, a plurality of cards 29 and 30 are to be provided for the holders 24. These cards are to be employed in pairs and one of the cards 29, which is much longer than a companion card 30 is first inserted downwardly of the upper open ends of the channel-ways formed by the flanges 24' to seated position 50 therein with its lower edge resting on the bottom flange 24". In this position of the card 29, a sufficient space within the holder will be available at its upper end to receive the companion card 30 therein which will in turn, rest on the top edge of the card 29. Each of the cards 29, in the present adaptation of the apparatus, will have tabulated thereon a ready reckoned 55 selling price per unit weight or other measure of a given commodity, the latter being indicated by name or reference character on the companion card 30, together with the zone designation in which the selling prices hold good at the moment.

60 75 75 In the adaptation of the device for use in the

ready reckoning of the fluctuations in prices, including rates and commissions in different localities or zones from a basic or central zone, as in the case of grains and feeds distributed from stores and warehouses from which the customer 80 is supplied, the face plate 21 will also be marked at one side, preferably the left side of the uppermost of the slots 21', as at "X", to indicate the point at which the basic zone price is to be read from the tape 20; the next lowest slot "Y" to indicate the point at which the selling price including the rate of that particular zone in which the device is at the moment located; and the next lower slots "Z", "Z'" and "Z'" in the downward sequence of the same to indicate the added commission charges for instance, \$1, \$2 and \$3. 85 90

95 The tape 20 to be exposed through the slots 21', in the face plate 21 and the transparent cover 22', will have two columns or tabulations thereon, the one to the left hand side thereof, in the present instance, being the price range of the different feeds and grains per ton or other major unit of measure for the several localities or zones covered by the same and the right-hand side the proportionate prices per hundred weight or other 100 minor or fractional unit of measure. In the present method of distributing and selling feed or grain, it is to be noted that dairy feeds particularly are sold on the basis of cost per hundred weight (cwt) or percentage of digestible nutrient 105 content, and the cost or rate in each of the minor zones is subject to any fluctuation in the basic rate at the central zone, the percentage of which increase or decrease in rates varies in the increased distance of the minor zone from the central zone or in other words the basic rate is only good for the territory covered by the central zone. Therefore, for the present it will be assumed that in the minor zone nearest the central zone the basic rate will be subject to an increase of say 110 115 20¢ per ton of the commodities to be distributed and sold therein, 40¢ per ton in the second zone and 60¢ in the third zone, etc.

120 In accordance with this method of established rates for the different zones, the left-hand column on the tape 20, under the head "Ton" appearing on the face plate 21, will first indicate the basic zone selling price of, for instance, feed "E. W.", is \$47.05-\$47.20 inclusive, while second and at the right-hand side under "Cwt" the selling price of \$2.36 per hundred weight. Below these figures will appear \$47.65-\$47.80 at the left-hand side and \$2.39 at the right hand side, which indicates that the computation is based on the 60¢ or third zone rate of increase above the basic price per ton and that the basic hundred weight price is therefore increased by 3¢. The next lower figures \$48.65-\$48.80 on the left-hand side and \$2.44 on the right-hand side representing the zone selling prices per ton and hundred weight respectively, taking \$1. per ton for commission into account. Similarly, the next two lines of figures below take into account commission charges of \$2. and \$3. per ton respectively, by the inclusion of which commissions give the per hundred weight prices as \$2.49 and \$2.54. 130 135 140

145 Thus, with these tabulations arranged in column groups, the tape 20 may be moved to bring the proper basic price of a particular commodity in a selected zone into registration with the uppermost of the slots 21' in the face plate 21, upon a turning movement of the main roller 16 from the finger piece 16' when the said price, with the added rate of increase and allowed com- 150

missions, will appear at the lower sight openings or slots 21'.

For each commodity to be handled by the apparatus, an identification or name card 30 will be provided along with a companion hundred weight price card 29, on which will first appear a computed hundred weight price of a particular commodity, taken from the right-hand side of the tape 20 for the zone in which the apparatus

10 is employed at the moment.

In the operation of the apparatus as thus constructed and arranged, and the operator in a minor zone gets word of a change in rate in the price of a particular commodity over the basic 15 price at the central zone, he will first manipulate the finger piece 16' of the roller 16 to move the tape 20 to a position relatively to the face plate 21, where the basic price per ton of the commodity at the central zone will appear at the left-hand 20 side of the uppermost of the slots 21', or as at "X", when he will then read at the slot "Y" the basic selling price plus the increase for his particular zone and at the slots "Z", "Z'" and "Z''" the increased selling price plus the commission 25 allowed. At the same time, he will also observe at the right-hand side of these slots the prices per hundred weight of the commodity. If the commission allowed him is a \$1, as in the first minor zone, he will get his final reading per ton 30 and per hundred weight at the third slot from the top of the face plate 21, designated at "Z". With the selling price of each commodity known, including the zone rate and commission, the operator will now select the individual rate cards 35 29 and companion name cards 30, the former each bearing a table of current prices per hundred weight of a particular commodity and will arrange the same in the card holders 24, so that, when an order is received for say three hundred 40 weight of the feed "E. W.", as indicated on a card 30, the exact price of that amount of the commodity will be read directly from the table on the companion card 29.

It is to be noted that the two uppermost of the 45 slotted openings 21' are spaced somewhat closer together than are the lower of these two openings and the remainder thereof below the same, which are equidistantly spaced apart. This arrangement is necessary in order that the related 50 items of indicia on the tape 20 will be exposed in a proper sequence, as hereinbefore stated.

It will be understood that the limit in number

of commodities to be priced with the apparatus will be governed only by the number of card holders 24 employed in the cabinet section 11, and that there will be a group of tabulations on the tape 20 covering a fairly wide range of price fluctuations in order that the lowest and highest possible prices of all of the several commodities shown on the indicating or name card and companion rate card may be read therefrom.

Without further description, it is thought that the features and advantages of the invention will be readily apparent to those skilled in the art, and it will of course be understood that changes in the form, proportion and minor details of construction may be resorted to, without departing from the spirit of the invention or its scope as claimed.

I claim:

1. In a device of the class described, a movable tape having a column of price tabulations thereon relating to a plurality of commodities, said tabulations including separate items of basic price of a major unit of weight or measure of each commodity, the basic price plus a predetermined rate of increase over such basic price and the latter plus allowed commissions, means movably mounting said tape whereby these related items only may be exposed to view for any one of the several commodities, and a separate column of graduated price tabulations of fractional units of weight of each commodity computed from the other of said price tabulations.

2. In a device of the class described, a cabinet, an endless tape within said cabinet and having a column of price tabulations thereon relating to a plurality of commodities, said tabulations including separate items of basic price of each commodity, the basic price plus a predetermined increase over such basic price and the latter plus allowed commissions, a separate column of graduated price tabulations of fractional units of weight of each commodity computed from the other of said price tabulations, and means for moving said tape whereby to expose to view at the front side of said cabinet the related items only of any one of the several commodities, said cabinet having a plurality of unevenly spaced sight openings therein for the exposure of certain related and computed tabulations therethrough upon each movement of said tape.

EDWARD STANLEY GRIFFITH.
